UNITED STATES PATENT OFFICE.

FRANK GALIK, OF FAIRGROVE, MICHIGAN.

COMBINED WARDROBE AND BED.

Application filed December 6, 1923. Serial No. 678,882.

To all whom it may concern:

Be it known that I, FRANK GALIK, a citizen of Hungary, residing at Fairgrove, in the county of Tuscola and State of Michigan, have invented certain new and useful Improvements in Combined Wardrobes and Beds, of which the following is a specification.

This invention relates to certain new and useful improvements in combined wardrobes and beds wherein a structure embodying hinged sections is adapted to function as a wardrobe when in a set up vertical position and is adapted to be moved on its hinge connection for assuming a horizontal position for use as a bed.

A further object of the invention is to provide a combined wardrobe and bed embodying a base structure having a sliding drawer therein and an upper structure hinged to the base structure with a central longitudinal partition dividing the upper section into a front wardrobe compartment and a rear compartment containing a bed spring with an upper front decorative panel board for the upper section hingedly mounted thereon and adapted to be moved to a position as a support for the outer end of the upper section when moved on its hinge connection with the base section.

With the above general objects in view and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a front elevational view of a combined wardrobe and bed constructed in accordance with the present invention, the device being illustrated in a set-up position as a wardrobe,

Figure 2 is a side elevational view thereof,

Figure 3 is a side elevational view of the device moved to the position of a bed,

Figure 4 is a longitudinal sectional view taken on line IV—IV of Fig. 5,

Figure 5 is a top plan view of the device in the position of a bed,

Figure 6 is a detail sectional view taken on line VI—VI of Fig. 1, and

Figure 7 is a fragmentary side elevational view and a cross sectional view of a curtain

or screen with supporting roller for covering the rear side of the structure when set up as a wardrobe and shown in Fig. 2.

The device embodies a base structure 60 having a bottom wall 1, end walls 2, a front wall 3 and a relatively high rear wall 4 that constitutes a head board when the device is set up in position as a bed. The front wall 3 of the base structure has an opening there- 65 in for the sliding reception of the drawer 5 while a transverse bar 6 extends between the end walls 2 and overlies the drawer when in a closed position as shown in Figs. 4 and 6.

The upper structure is hinged to the forward upper edge of the base structure and includes side walls 7 connected by a bottom wall 8 and an upper wall 9 and a front wall 10. The lower end of the front wall 10 is 70 hinged at 11 to the upper front edge of the base structure and the entire upper structure of the device swings forwardly on its hinge mounting as illustrated in Figs. 3 75 and 4.

A longitudinally extending vertical partition 12 extends between the bottom and top walls 8 and 9 to divide the upper structure into a forward wardrobe compartment and a rear bed spring and mattress compartment. Hinged doors 13 are carried by the front wall 10 and terminate at their upper ends adjacent the transverse partition shelf 14 extending between the side walls 7, the partition 12 forming an upper compartment 15 and a lower compartment 16, the partition wall 12 carrying clothes hooks 17 adjacent to and beneath the partition 14 as shown in Fig. 4. The closure for the upper compartment 15 is in the form of a panel board 18 hinged as at 19 to the forward edge of the upper wall 9 and carries an upper extension 18^a extending above the upper wall 9 as shown in Fig. 2.

A bed spring supporting frame including 100 side rails 20 and transverse end bars 21 and 22 supports a metallic spring 23 with the forward transverse bar 22 secured as at 24 to the side walls 7 adjacent the upper wall 9 of the upper structure rearwardly of the 105 partition 12 with the other transverse bar 21 positioned below the bottom wall 8 of the upper structure and between lower end extensions 7^a of the side walls 7. The side rails 20 rest upon the rear face of the partition 12 when the device is set up as a bed 110 as shown in Fig. 4 and is disposed in the

compartment 25 rearwardly of the partition 12. The lower face of the upper wall 9 adjacent the rear edge thereof carries a plurality of eye bolts 26 by which a mattress may be supported when the upper structure is vertically positioned as a wardrobe as shown in Figs. 1 and 2.

The rear wall 4 of the base structure terminates at a point below the upper end of 10 the upper hinged structure as shown in Fig. 2 and a flexible screen or curtain covering is provided for the entire rear side of the device, a casing 27 carried by the rear edge of the upper wall 9 enclosing a roller 15 28 upon which a curtain 29 is wound, the free edge of the curtain carrying an eye 30 for engaging the hook 31 secured to the lower edge of the rear wall 4 as shown in Fig. 2 for completely closing the rear side 20 of the device.

When it is desired to convert the device from the wardrobe position shown in Fig. 2 to the bed position shown in Fig. 3, the curtain 29 is disengaged from the hook 31 25 and wound upon the roller 28 and the upper structure moved on its hinge connection 11 with the base structure to a horizontal position. The panel board 18 is also moved upon its hinge mounting 19 with the extension 18^a thereof engaging the upper face 30 of the upper wall 9 as shown in Figs. 3 and 4 while the lower edge of the panel board 18 constitutes a foot support for the outer free swinging end of the upper structure, the 35 panel board being retained in this position by the hook 32 secured at one end as at 33 in the compartment 15 with the hook end thereof engaging the eye 34 carried by the inner face of the panel board 18. A pillow board 35 is hinged as at 36 to the inner face 40 of the rear wall 4 of the base structure and is moved forwardly with the rear wall 4 of the base structure and when the upper structure is lowered the forwardly bevelled edge 45 of the pillow board 35 rests upon the bevelled edge of the adjacent transverse bar 21 of the bed spring frame. The relative positions of the pillow board 35 and the transverse bar 21 of the spring frame, when the upper

structure is raised, are shown in Figure 6, the 50 adjacent contact edges of the transverse bar 21 and pillow board 35 being beveled, automatic tipping of the board to the position shown in Figure 6 is accomplished when the 55 spring frame is elevated. When the free edge of the board passes beyond the transverse bar, the same engages the spring bottom 23 and is moved thereover upon continued movement of the upper structure to be 60 displaced as shown and not to interfere with the upward movement of the upper structure. It will therefore be seen that movement of the pillow board is secondary in operation to the movement of the upper structure and is gravitationally restored to its 65 operative horizontal position when the upper structure is lowered. A rigid bed structure is thus provided, the panel board 18 offering a rigid support for the free swinging end of the upper structure while the 70 board 15 properly supports a pillow in conjunction with the mattress mounted upon the spring 23.

While there is herein shown and described the preferred embodiment of the present invention it is nevertheless to be understood that minor changes may be made therein without departing from the spirit and scope of the invention as claimed.

What is claimed as new is:—

In a combined wardrobe and bed, a base structure, an upper structure hinged thereto in the form of a combined wardrobe and bed, the upper structure supporting a bed spring having transverse end rails with the upper edge of the rail adjacent the base being bevelled, and a pillow board hinged to the base and having a forward bevelled edge supported on the bevelled edge of the bed rail when the bed is lowered the bevels being so arranged that the upward folding movement of the bed displaces the pillow board from the bed rail and folds it upwardly.

In testimony whereof I affix my signature.

FRANK GALIK.
